BERNARD R. LE ROY, OF ZANESVILLE, OHIO.

CUSPIDOR-HANDLING DEVICE.

1,282,246.

Specification of Letters Patent. Patented Oct. 22, 1918.

Application filed March 12, 1917. Serial No. 154,250.

To all whom it may concern:

Be it known that I, BERNARD R. LE ROY, a citizen of the United States, residing at Zanesville, in the county of Muskingum and

5 State of Ohio, have invented certain new and useful Improvements in Cuspidor-Handling Devices, of which the following is a specification.

The present invention relates to cuspidor handling devices and has for its main object, 10 the provision of a simple effective device for accomplishing the purposes of the invention.

The invention resides in the provision of a single device consisting of a cleaning implement and a cuspidor gripping implement closely and so associated that the device may be rapidly manipulated to clean or swab cuspidors and to grasp the latter so that it may be conveyed from place to place without 20 contact with the hand.

The feature of the invention is in the provision of a twisted or threaded rod having a swab on one end thereof, and in the provision of a pair of gripping tongs on the other 25 end of the rod normally held open and adapted to be closed manually, the rod being rotated by a slideable block thereon so as to facilitate the swabbing or cleaning of the cuspidor.

30 Another feature resides in loosely mounting the gripping tongs on the rod in order that the latter may be rotated relative thereto, the gripping tongs thus providing a handle for holding the rod in operative position while being rotated by the slideable block.

Other features will be apparent from the construction, combination and arrangement of parts which will be hereinafter more fully 40 described and finally pointed out in the appended claims.

In the drawings which illustrate the preferred embodiment of the invention:—

45 Figure 1 is a front elevation of the device constructed in accordance with the invention, and illustrating it in the position when it performs the swabbing or cleaning operation,

50 Fig. 2 is a fragmentary front elevation partly in section to illustrate the detailed construction and connection of the gripping tongs on the rod,

Fig. 3 is a detail view taken substantially on line 3—3 of Fig. 2, and

55 Fig. 4 is a sectional view of the sliding block.

Like characters denote similar and like parts throughout the specification and drawings.

Referring particularly to the drawings the 60 device constructed in accordance with the invention comprises, in its preferred form, a rod 1 carrying at its lower end a brush member or swab 2. The rod 1 is twisted or otherwise threaded to be acted upon by the block 65 3 slidably mounted on the rod 1 and movable thereon throughout its length. The bore in the block 3 has a portion thereof substantially square as shown at 4 in Fig. 4 so as to provide angular walls which will coöperate 70 with the threads on the rod 1 in order that when the block 3 is moved back and forth on the rod, a rotary motion, or better an oscillating motion, will be imparted to the rod. Thus, manifestly a swabbing operation of 75 the cuspidors can be accomplished by reciprocating or moving the block 3 back and forth on the rod 1.

A handle member for the rod is provided by the grasping means 5 loosely carried on 80 the opposite end of the rod 1. The connection between the grasping means 5 and the rod is provided by a sleeve 6 loose upon a reduced portion 7 of the upper end of the rod and a washer or plate 8 is secured to the extremity of the reduced end so as to retain the sleeve 6 upon the rod, the washer 8 being of a larger diameter than that of the diameter of the rod 1. As the sleeve 6 is loosely mounted, it may be rotated on the reduced 90 end of the rod 1.

The grasping means comprises a stationary tong 9 having a curved jaw *a* at one end and a tubular extension *b* at the other end and connected together by an intermediate 95 shank portion *c*. The tubular member *b* is internally threaded for engagement with the sleeve 6 as shown in Fig. 2. The grasping means 5 also comprises a pivoted tong 10 having a shank portion *c* and a curved 100 jaw *a* to coöperate with the jaw *a* of the tong 9. The lower end of the shank of the tong 10 is pivoted within the tubular member as indicated at 11. It is to be understood that the extension *b* may be tubular or otherwise that will permit the construction herein recited. The shanks *c* of the tongs are roughened to facilitate the grasping by the hand so that the tongs may be moved together to the position shown in Fig. 2. It 110 will also be seen that when it is desired to use the device for the purpose of cleaning

the cuspidor, the roughened shank portions *c* of the tongs are grasped while the block 3 is reciprocated on the rod 1. The loop member 12 surrounds the shanks *c* of the tongs 5 and its arms are curved in cross section, as shown in Fig. 3, so as to form a casing or retainer for a coil spring 13 disposed between the arms of the loop. It will be noted that with this construction, the spring 10 13 will move and normally hold the jaws in open position relative to each other and when it is desired to grasp a cuspidor for the purposes of transporting it from place to place, the jaws *a* of the tongs are placed 15 about the cuspidor and the shank portions grasped by the hand and moved together. It may be found desirable however, to provide a leaf spring between the tongs instead of the means herein shown.

20 From the foregoing, it will be clear that a novel device is provided which will be found most desirable in the cleaning and handling of cuspidors and whose parts are so associated that it may be operated with 25 great facility. It is to be understood that certain changes in the construction combination and arrangement of parts may be resorted to that fall within the legitimate scope of the appended claims.

30 What is claimed is:—

1. A cuspidor handling device comprising in combination with a handle, a curved stationary jaw secured to the handle, a second curved jaw pivotally connected to the handle, a loop formed on the stationary jaw 35 and encircling the pivoted jaw, said loop having its inner faces concaved, and a coil spring received between the two jaws and adapted to be received in the concaved portion of the loop.

40 2. A cuspidor handling device comprising in combination with a handle, a casting secured to the top of the handle and having a

recess in the top face thereof, a curved stationary jaw formed integral with the casting, a second curved jaw co-acting with the first mentioned jaw, the lower end of the second mentioned jaw being received in the recess in the top of the casting, means passing through the casting and end of the second 45 jaw for pivotally connecting the same, and a coil spring received and held between the two jaws.

3. A cuspidor handling device comprising in combination with a handle having a sleeve 55 rotatable on one end thereof, a casting secured to the rotatable sleeve, a curved jaw formed integral with the casting, a second curved jaw pivotally connected to the casting and co-operating with the stationary jaw, 60 a loop formed integral with the stationary jaw and encircling the pivoted jaw, said loop having its inner faces concaved, and a coil spring received between the jaws and held in the concaved portion of the loop.

4. A cuspidor handling device comprising in combination with a handle having a sleeve rotatable thereon, a casting secured to the sleeve, a curved jaw formed integral with the casting, said curved jaw having a 70 recess therein, a second jaw pivotally connected to the casting and provided with a recess in alignment with the recess of the stationary jaw, a loop member formed integral with the stationary jaw and encircling the 75 pivoted jaw, and a coil spring received between the two jaws, the ends of said spring being received in the recesses formed in the jaws.

In testimony whereof I affix my signature 80 in presence of two witnesses.

BERNARD R. LE ROY.
